Patented Apr. 27, 1971

220,572

ANIMAL EXERCISER

Samuel Rosenberg, Brooklyn, N.Y., assignor to Excelsior
Pet Products, Inc., Brooklyn, N.Y.

Filed Oct. 13, 1969, Ser. No. 19,528

Term of patent 14 years

Int. Cl. D30—99

U.S. Cl. D30—42

FIG. 1

FIG. 2

FIG. 3

FIG. 4

FIG. 5

FIG. 6

FIG. 1 is a top plan view of an animal exerciser embodying my design;

FIG. 2 is an end elevational view of one end thereof;

FIG. 3 is a side elevational view of one side thereof;

FIG. 4 is a bottom plan view thereof;

FIG. 5 is a side elevational view of the side opposite the side shown in FIG. 3; and

FIG. 6 is an end elevational view of the end opposite the end shown in FIG. 2.

I claim:
The ornamental design for an animal exerciser, substantially as shown and described.
